UNITED STATES PATENT OFFICE.

SAMUEL BERGSTEIN AND ALBERT ELLSWORTH DUVALL, OF MIDDLETOWN, OHIO, AS-SIGNORS TO THE INTERSTATE FOLDING BOX COMPANY, OF MIDDLETOWN, OHIO.

PAPER-BOX-MAKING MACHINE OR THE LIKE.

Application filed October 8, 1924. Serial No. 742,324.

To all whom it may concern:

Be it known that we, SAMUEL BERGSTEIN and ALBERT ELLSWORTH DUVALL, citizens of the United States, residing at Middletown, 5 in the county of Butler and State of Ohio, have invented certain new and useful Improvements in Paper-Box-Making Machines or the like, of which the following is a specification, reference being had thereto in the accompanying drawings.

This invention relates to paper box making machines, having particular reference to machines of the type illustrated in a co-pending application for Letters Patent, Ser. 15 No. 722,330, filed June 25, 1924, in which one of the joint inventors in the present case is the applicant.

Box making machines of this character are of the semi-automatic type, and are 20 adapted for general use in manufacturing paper boxes in quantities, but more especially to the requirements of users of boxes in relatively smaller quantities who are enabled, by means of the simple, low-cost machines, to make their own boxes, in whatever quantities required, as needed and at lower cost than the same could be obtained from manufacturers on small quantity orders.

30 To this end, the machines must be of simple construction and operation, and adaptable for making boxes of variable shapes and sizes. The boxes produced on the machines must also possess the quality 35 of the average product of this character.

It is also essential in these semi-automatic machines that adequate provision be made for safety of operation, this being particularly important in view of the fact that the 40 machines are frequently in charge of inexperienced operators.

The objects attained in our invention, therefore, are,—first, a machine which is 45 simply constructed, and which can be manufactured and sold at low cost; second, a machine which is safe to operate and which can be operated with facility by the inexperienced operator; third, a machine which is adaptable for making paper boxes 50 of various shapes and sizes; and fourth, a machine which is adapted for making paper boxes of first quality, with the foldings for

shaping the boxes made accurately and all joints firmly glued to insure the strength and uniformity of construction required in 55 the use of the product.

In the machine of the present invention, as in the machine which forms the subject matter of the copending application herein referred to, the glued joints of the boxes 60 are made under pressure to the end that the joints are firmly knitted together, and the fibrous material of the coating joint surfaces is caused to intermesh to sufficient extent to firmly unite the parts, making in 65 effect an integral portion of multiple strength of the parts glued together.

Also in the machine of the present construction, as in the earlier machine herein referred to, gluing mechanism is used which 70 is especially adaptable to the conditions of use of machines of this character. No features of added novelty, however, with respect to the gluing mechanism are embodied in the present invention, this feature 75 of the machine being herein shown and described in its general application only as a means to comprehensive description of the construction and operation of the machine as a whole.

80 In the accompanying drawings, the improved machine is shown in a preferred form which serves to illustrate our invention as set forth and comprehended in the appended claims.

85 In the drawings:

Fig. 1 is a side elevation of the machine;

Fig. 2 is a sectional view of the machine showing a plan of the box forming work head;

Fig. 3 is a detail side elevation of the work head;

Fig. 4 is a detail view of the pressure head;

Fig. 5 is a vertical sectional view of the 95 machine;

Fig. 6 is a detail view of the box folding mechanism;

Fig. 7 is a plan view of the box forming block;

Fig. 8 is a sectional view of the box forming 100 block;

Fig. 9 is a plan view of the box forming block in modified form;

Fig. 10 is an end view of Fig. 9.

The box making machine, as here shown, comprises a vertical, hollow column 1, having a base 2, which serves to support the 5 operable mechanism which comprise a rotatable work head 3, mounted on column 1 concentrically to the axis thereof; gluing mechanism 4 for supplying an adhesive to the box blanks for forming the joints of 10 the boxes; a pressure head 5 for completing the joints; operating shaft 6 for reciprocating the pressure head and the gluing mechanism, gearing 7 operatively connected to the main operating shaft 6 and timed to effect a 15 step-by-step rotation of the work head, and detail mechanisms associated with these main units of the machine which will presently be described herein in detail.

The machine may be operatively connected 20 to any suitable source of power, as the motor 8, which as here shown is connected to a power and balance wheel 9 by reduction gearing 9^a in a ratio suited to the operation of the machine,—the power wheel being 25 in turn connected by reduction gearing 10—11, drive shaft 6 and bevel gears 12—13 to a drive shaft 14, which is extended downward through column 1, and connected to gearing 7 by means of bevel gears 15—16. 30 Gear 16 is connected to operate in unison with a disc or pin gear 17 and a cam 18,—the gear and cam acting to impart step-by-step movement through gears 19, 24, 25, 26 and 27 to the operating head 3,—gears 35 26—27 being bevel gears to adapt the movement to the right-angle connection with the work head, and gear 24 being supported on a pivoted arm 28 to provide for change of gearing to vary the speed of operation. 40 Gear 19 has secured to its inner face a star gear 20 which coacts with parts 17—18 in a Geneva-lock movement,—the driving relation between the parts being accomplished by means of a pin 21 in disc 17 and radial 45 slots 23 in the star gear 20 which are adapted to be engaged successively by pin 21, cam 18 coacting successively with oppositely arranged cams 22 in the periphery of gear 20 intermediate slots 23, to bring the mechanism to a positive stop upon each quarter turn of gear 19 and to provide a pause in the rotation of the work head upon each quarter turn thereof to enable the machine attendant to position a box blank on the work head, to 50 align units of the work head, and to maintain the work head in a position of rest during the operation of the gluing and pressure mechanisms.

Gear 11 is mounted, by any suitable 60 means, as the usual arrangement of tight-and-loose pulleys, to run normally idle,—a treadle 29 in the base of the machine and the usual shot-bolt connection 29^a being employed to effect operating relation between 65 the gear and shaft 6.

As best shown in Fig. 2, the work head of the machine comprises four radial arms 32 and four units of box supporting mechanism 30, each unit consisting of a base 31 which is adapted to have a portion of the 70 box, as an end to be folded and glued, positioned thereon by the attendant operator,—spring clips 33 being arranged on opposite sides of the bases to retain the boxes in position thereon by frictional engagement during the gluing and joint forming operations and until the same are removed upon completion of the cycle of operation.

Provision is made in the mounting of the box retaining clips to adapt the same to 80 boxes of variable sizes, the means consisting of rods 34 supported in brackets 35 on arms 32, and adjustable clip holders 36 supported on rods 34 and adapted to be shifted axially thereon as desired to suit the size of a box 85 to be made on the machine.

The bases 31 are also adjustable,—the same being adapted to be set at right angles to the position shown to adapt the same for supporting both units of the box-top and bottom portions—which usually vary more or less in their corresponding dimensions,—provision being also made by the same arrangement to use bases 31 of different sizes 90 interchangeably one with another.

As illustrated in Fig. 2, the work head has four work supporting units of identical construction which, when the machine is at rest, occupy positions A, B, C and D respectively, the attendant serving the machine in position A and the direction of operation being counter-clockwise as indicated by the arrow. In this position opposite, outwardly extended guides 37 are provided to position the box 100 for height on the box supporting mechanisms 30 so that the folds for forming the joints will be made uniform on all the boxes. To this end, arms 37 are formed concave, V-shaped as here shown, on their under side 105 to receive the open, upward extended flaps —a of the end of the box and to retain the same in vertical position until the first step of folding has been made. Arms 37 are supported on a bar 38 which is slotted as at 39 to permit of varying the spacing of the arms relative to each other to suit the width of the box for which the adjustment is made,—bar 38 being in turn supported by a block 40 adjustable vertically on a rod 41 secured in a plate 42 fixed to the head support of the machine, whereby to set the arms 37 according to the height of the end flap —a of the box.

An arm 43 is pivoted on rod 41 at its base and in its idle position is drawn in 125 clockwise direction against a stop 44 by a spring 45,—the arm having secured therein a rearwardly extended, curved rod 46 which in turn has a finger 47 and curved rod 48 secured thereto, the rod 48 being 130

adjustable on rod 46 longitudinally thereof. This mechanism serves to effect the first fold of the box,—a lug 49 extended upwardly from each end of the box carrying units 30 acting upon rotation of the work head to engage the finger 47 and thus to rock arm 43 on its pivot center and to move arm 48 forward, in advance of the movement of the work head, into engagement with the adjacent end flap —a of the box at right angles over the edge of base plate 31, spring 45 acting to retract arm 43 as lugs 49 pass out of engagement with finger 47.

15 The opposite end flap —a, upon rotation of the work head, is moved out of engagement with the other arm 37 and upon further advancement of the work head is brought into engagement with a circumferentially extended tubular rod 49^b supported outwardly of the machine on brackets 50—51 in a plane and in a manner to effect a corresponding fold of the opposite flap —a, both flaps —a being then retained 25 in folded relation as the unit supporting the box moves to position B. Brackets 50—51 are slotted as at 52—53 and tubular rod is arranged telescopically with a second rod 49^a to permit of adjusting the rods 30 radially relative to the work head to suit variations in the size of boxes.

The adhesive for forming the joints is applied to flaps —a in position B,—the mechanism for applying the adhesive being substantially the same as that described in the copending application for patent herein referred to, no novelty being claimed relative to the details of the mechanism as here shown. Only such description of the mechanism, therefore, will be made herein as applies to the general application thereof to the machine as a whole. The mechanism consists of a container 54 of suitable capacity for liquid glue or any other adhesive. The container is provided in the bottom thereof with a series of ports each controlled by a spring-tensioned valve stem 55 for delivering a deposit of glue upon the folded flaps of the box. To this end, the mechanism has a vertical, reciprocal movement, the projecting ends of the valve stems being brought into contact with the folded end of the box in the downward movement of the mechanism which causes the ports to be opened and a deposit of adhesive to be made from the end of each valve stem, the adhesive being thus more or less evenly distributed in measured amount over the flaps preliminary to forming the joints.

60 Position C of the machine as here shown is an idle position. The work as it is moved from position B passes out of engagement with rod 49^a under a similarly arranged rod 49^b which is supported at its opposite end 65 in a slotted extension 53^a of bracket 51, and

thence into an open space E in which the coacting end flap —b is brought into engagement with an arm 56 which acts to effect a fold thereof at right-angles to and over flaps —a as the work head moves to position 70 D,—the folded end of the box passing under the pressure head 5 which upon the next stroke of the machine acts to form the joint by pressing the folded end portions a—b firmly together.

75 Vertical reciprocal action is imparted simultaneously to the gluing and pressure mechanisms, as here shown, by eccentric connections 57—58 with shaft 6, the details of the arrangement being of well known 80 construction. To adapt the gluing mechanism to variations in size and in the character of the folds of the portions of the box to be glued together, the mechanism is supported adjustably on a rod 59 secured in 85 opposite arms 60 which provides for a range of adjustment to meet all normal variations of size and construction.

90 The detail Fig. 6 illustrates the manner of supporting the box folding arm 48 yielding-ly by pivoting the arm at 62 in a bifurcated arm 61 secured to arm 66, arm 48 being retained in normal relation by a spring 63 engaging a pin 64,—the provision being made as a safety feature to guard against 95 injury to the hand of the operator if caught between arm 48 and block 31.

95 From the foregoing detailed description and the illustrations of the drawings, the improved machine, as specifically defined and comprehended as to principle in the appended claims, will be readily understood by those experienced in the art to which our invention pertains.

100 As best shown in detail Figs. 7 to 10, the box forming blocks —31 are preferably provided with corrugations along opposite edges of the block, as shown at 71 in Figs. 9 and 10, or with a pyramided surface, as shown at 105 67 in Figs. 7 and 8 which act in either construction to effect an intermeshing of the coacting surfaces of the paper stock at the joints as the same are formed under pressure. This arrangement has the double advantage of effecting a positive intermeshing 110 of the stock at relatively low pressure and therefore with less labor on the machine as the joints are formed, and also acts to prevent opening or spreading of the joints before the glue sets. The joints formed in 115 this manner are also far superior to the ordinary flat-surface glued joint by reason of the fact that the glue between the corrugated or pyramided surfaces forms in effect a solid adhesion between the overlapping flaps with the result that the portions of the box thus joined together become integral and have the strength of multiple thickness of the paper stock.

120 125 130 As best shown in detail Fig. 8; a spring

element is interposed between the forming block 31 and the supporting arm 32 to adapt the forming mechanism to variations in the thickness of the stock, and also to variations 5 in the forming mechanism itself, and also to relieve the mechanism of excessive stress during the forming operation. The mechanism as here shown consists of springs 68, arranged adjacent the corners of block 31, 10 and adjusting screws 69 which extend free through arm 32 and are threaded into block 31 thus providing for adjustment of the spring tension on the blocks, arm 32 being counterbored as at 70 to form a seat for the 15 springs.

Having described our invention, we claim:

1. A paper box making machine including in combination a rotatable work head 20 adapted to be moved successively into positions of rest and comprising a plurality of work supporting units, and means associated with each of said units in one of said positions to adjust the boxes for height 25 as the same are placed on said work supporting units.

2. A paper box making machine including the combination a rotatable work head adapted to be moved successively into positions of rest and comprising a plurality of work supporting units, and means associated with each of said units in one of said 30 positions adapted to engage foldable portions of the boxes and to adjust the boxes 35 for height as the same are placed on said work supporting units.

3. A paper box making machine including in combination a rotatable work head adapted to be moved successively into positions 40 of rest and comprising a plurality of work supporting units, and means associated with each of said units in one of said positions adapted to engage opposite, foldable flaps of the boxes whereby to position 45 the boxes for folding as the same are placed on said work supporting units.

4. A paper box making machine including in combination a rotatable work head adapted to be moved successively into positions 50 of rest and comprising a plurality of work supporting units, and means associated with each of said units in one of said positions adapted to engage and align opposite foldable flaps of the boxes whereby 55 to position the boxes for folding as the same are placed on said work supporting units.

5. A paper box making machine including in combination a rotatable work head 60 adapted to be moved successively into positions of rest and comprising a plurality of work supporting units, and means consisting of members arranged oppositely one with the other and extended outwardly to 65 engage opposite, extended flaps of the boxes

as the same are placed on said work supporting units whereby to position the boxes thereon for folding.

6. A paper box making machine including in combination a rotatable work head 70 adapted to be moved successively into positions of rest and comprising a plurality of work supporting units, and means consisting of members arranged oppositely one of the other, extended outwardly and shaped 75 to engage and align opposite extended flaps of the boxes as the same are placed on said work supporting units whereby to position the boxes thereon for folding.

7. A paper box making machine including in combination, a rotatable work head adapted to be moved successively into positions of rest and comprising a plurality of work supporting units, and means associated with each of said units in one of said 85 positions and actuated incident to the rotation of the work head to effect a fold on a paper box positioned on a work supporting unit.

8. A paper box making machine including in combination, a rotatable work head adapted to be moved successively into positions of rest and comprising a plurality of work supporting units, and means associated with each of said units in one of said 95 positions and adapted to be actuated in advance of the movement of the work head to effect a fold on a paper box positioned on a work supporting unit.

9. A paper box making machine including in combination, a rotatable work head adapted to be moved successively into positions of rest and comprising a plurality of work supporting units, and means consisting of a spring tensioned pivoted member 100 associated with each of said units in one of said positions, adapted to be actuated incident to the rotation of the work head to effect a fold on a paper box positioned 105 on a work supporting unit.

10. A paper box making machine including in combination, a rotatable work head adapted to be moved successively into positions of rest and comprising a plurality of work supporting units, and means consisting of a pivoted member operable in a plane parallel to the plane of operation of the work head, associated with each of said units in one of said positions and adapted to be actuated in advance of the movement 110 of the work head to effect a fold on a paper box positioned on a work supporting unit.

11. A paper box making machine including in combination, a rotatable work head adapted to be moved successively into positions of rest and comprising a plurality of work supporting units, and a pivoted member adapted to be actuated positively in one direction and to be spring retracted in the opposite direction, associated with each of 115 120 125

- said units in one of said positions whereby to effect a fold on a paper box positioned on a work supporting unit.
12. A paper box making machine including in combination, a rotatable work head adapted to be moved successively into positions of rest and comprising a plurality of work supporting units adapted to be moved into progressive operative relations by said successive movements, a spring-tensioned member operable in one direction coactively with each of said units in one of said positions to effect a fold upon a paper box supported thereon, and yieldable in the opposite direction to an obstruction interposed in the plane of its said first named direction of operation.
13. A paper box making machine including in combination, a rotatable work head adapted to be moved successively into positions of rest and comprising a plurality of work supporting units, means associated with each of said units in one of said positions to effect an initial fold on a box positioned on a work supporting unit, and means interposed between said position and the adjacent position of rest, in the direction of rotation of the work head, adapted to effect a second fold on said box.
14. A paper box making machine including in combination, a rotatable work head adapted to be moved successively into positions of rest and comprising a plurality of work supporting units, means associated with each of said units in one of said positions to effect an initial fold on a box positioned on a work supporting unit, and means consisting of a member supported in a plane above and parallel to the plane of rotation of the work head, interposed between two positions of rest and acting to effect a second fold on said box.
15. A paper box making machine including in combination, a rotatable work head adapted to be moved successively into positions of rest and comprising a plurality of work supporting units, means associated with each of said units in one of said positions to effect an initial fold on a box positioned on a work supporting unit, and means consisting of a member supported in a plane above and parallel to the plane of rotation of the work head, interposed between two positions of rest, acting to effect a second fold of like character on the box and to retain the folds in said relation by frictional contact therewith.
16. A paper box making machine including in combination, a rotatable work head adapted to be moved successively into positions of rest and comprising a plurality of work supporting units, means associated with each of said units in one of said positions to effect an initial fold on a box posi-
- tioned on a work supporting unit, and means consisting of a member supported in a plane above and parallel to the plane of rotation of the work head, interposed between two positions of rest in the path of the work supporting units, acting to effect a second fold on the box and to retain the folds in folded relation, and means to adjust said member relative to the work supporting units to suit the size of the boxes thereon.
17. A paper box making machine, including in combination a rotatable work head comprising a plurality of work supporting units, and adapted to be moved successively into positions of rest, means associated with each of said heads in one of said positions to effect an initial fold on a box positioned on a work supporting unit, means arranged along the path of rotation of the work supporting units to effect a second fold of like character on said box, and means arranged further along said path of rotation to effect a fold on said box to overlap said first folds.
18. A paper box making machine, including in combination a rotatable work head comprising a plurality of work supporting units, and adapted to be moved successively into positions of rest, means associated with each of said heads in one of said positions to effect an initial fold on a box positioned on a work supporting unit, means arranged along the path of rotation of the work supporting units to effect a second fold of like character on said box, and means arranged further along said path of rotation to effect a fold on said box at an angle to and overlapping said first folds.
19. A paper box making machine, including in combination a rotatable work head comprising a plurality of work supporting units, and adapted to be moved successively into positions of rest, means associated with each of said heads in one of said positions to effect an initial fold on a box positioned on a work supporting unit, means arranged along the path of rotation of the work supporting units to effect a second fold of like character on said box, and means consisting of a member supported above and further along said path of rotation and adapted to engage the paper box and effect a fold thereon overlapping said first folds.
20. A paper box making machine, including in combination a rotatable work head comprising a plurality of work supporting units, and adapted to be moved successively into positions of rest, means associated with each of said heads in one of said positions to effect an initial fold on a box positioned on a work supporting unit, means arranged along the path of rotation of the work supporting units to effect a second fold of like character on said box, and means consisting of a rigid member supported above and fur-

ther along said path of rotation and adapted to engage the paper box by frictional contact and to effect a fold thereon overlapping said first folds.

5 21. A paper box making machine including in combination, a rotatable work head comprising a plurality of work supporting units and adapted to be moved successively into positions of rest, means in one of said 10 positions to effect a fold on a box positioned on one of said supporting heads, means arranged along the path of said supporting heads to effect successive folds on said box, one fold overlapping another, and means in 15 other of said positions of rest for applying adhesive to and for forming adhesive joints between said folded portions of the box.

22. A paper box making machine including in combination with gluing and joint 20 forming mechanisms, a rotatable work head comprising a plurality of work supporting units, operating mechanism for the work head comprising interlocking gearing acting to rotate the work head in a step-by-step 25 movement and to bring the same successively into positions of rest with work supporting units in operative relation with said gluing and joint forming mechanism.

23. A paper box making machine including in combination with mechanism for 30 positioning a box on said machine for folding operations, and gluing and joint forming mechanisms, a rotatable work head comprising a plurality of work supporting units, operating mechanism for the work head comprising interlocking gearing acting to rotate the work head in a step-by-step movement and to bring the same successively into positions of rest whereby each of said work 35 supporting units is moved successively into operative relation with said first named mechanisms.

24. A paper box making machine including in combination with box supporting 45 mechanism, gluing mechanism for supplying an adhesive to portions of the box for forming a joint, and mechanism for forming said joint, comprising a box supporting member having projections on a surface 50 thereof coming in contact with coacting portions of the joints whereby said portions are caused to intermesh one with another as said joints are formed under pressure.

25. A paper box making machine includ-

ing in combination with box supporting 55 mechanism, gluing mechanism for supplying an adhesive to portions of the box for forming a joint, and mechanism for forming said joint, comprising a box supporting member having a corrugated surface coming in contact with coacting portions of the joints whereby said portions are caused to intermesh one with another as said joints are formed under pressure.

26. A paper box making machine including in combination with box supporting mechanism, gluing mechanism for supplying an adhesive to portions of the box for forming a joint, and mechanism for forming said joint, comprising a box supporting 60 member having corrugations arranged along opposite edges thereof with an intervening non-corrugated surface therebetween, coming in contact with coacting portions of the joints whereby intermeshed adhesive joints along said corrugated edges and said adhesive joints between said edges are effected as said joints are formed under pressure.

27. A paper box making machine including in combination with box supporting 65 mechanism, gluing mechanism for supplying an adhesive to portions of the box for forming a joint, and mechanism for forming said joint under pressure comprising a pressure mechanism and a box supporting member, and a resilient element associated with one of said parts whereby to effect compensation for variations in the paper stock as said parts coact one with the other as said 70 joints are formed therebetween.

28. A paper box making machine including in combination with box supporting mechanism, gluing mechanism for supplying an adhesive to portions of the box for forming a joint, and mechanism for forming 75 said joint under pressure comprising pressure mechanism and a box supporting member, a spring element associated with one of said parts whereby to effect compensation for variations in the paper stock and in said 80 mechanisms in their relation one to the other as said joints are formed therebetween, and means to regulate the tension of said spring element.

In testimony whereof, we affix our signatures.

SAMUEL BERGSTEIN.
ALBERT ELLSWORTH DUVALL.
